Filed Nov. 19, 1958, Ser. No. 774,972

4 Claims. (Cl. 103—117)

This invention is a rotary pump having a pump housing with end walls whose axial separation varies from a minimum at one side to a maximum at the opposite side of the axis of rotation. The impeller has axially projecting flexible blades confined between the end walls. At low speeds, the blades are flexed axially to vary the volume between adjacent blades and produce positive displacement pumping. At higher speeds, the blades are flexed by the fluid pressure away from contact with the housing end walls and a centrifugal pumping action is obtained.

In the drawings, Fig. 1 is an end view of an impeller; Fig. 2 is a section of line 2—2 of Fig. 1; Fig. 3 is an end view of a pump housing; Fig. 4 is a section of line 4—4 of Fig. 3; Fig. 5 is a diagrammatic perspective illustrating the position of the impeller blades during low speed pumping; Fig. 6 is a view similar to Fig. 2 but with the blades of unequal axial projection on opposite sides of the center disc; and Fig. 7 is an edge view of an impeller having blades of configuration for improved stress distribution.

The pump impeller has a metal hub 1 fixed to a drive shaft 2 and bonded to the center of a rubber disc 3 carrying integral axially projecting rubber blades 4 on opposite surfaces. The shaft 2 is journaled in opposite end walls 5 and 6 of a pump housing 7 and is provided with suitable seals 8. Surrounding the shaft 2 are axially projecting rubber sleeves 9 and 10 integral with the impeller which fit in recesses 11 and 12 of the end walls 5 and 6. The sleeves 9 and 10 rotate with the impeller and provide seals which increase in effectiveness during rotation due to the effect of centrifugal force which causes a slight expansion of the sleeves. The sealing action of the sleeves 9 and 10 is adequate for most applications so that the seals 8 may be omitted. The housing end walls 5 and 6 have integral tubular projections 13 and 14 which are received in slots or notches 15 and 16 in the blades 4 and which provide flexible outer sections 17 and 18 on the blades which are free to flex without stressing the disc 3 or the bonded connection to the hub 1. The blades 4 have the same diameter as the disc 3 and make sliding engagement with the outer peripheral wall 19 of the pump housing and also with the outer surfaces of the projections 13 and 14 which may be considered as the inner peripheral wall of the pump housing. The parts so far described are all concentric with the pump shaft 2.

The pump housing has two inlet connections 20, respectively on the upper and lower sides of the disc 3, and has two outlet connections 21 which are on the upper and lower sides of the disc. As shown more clearly in Fig. 4, the end walls 5 and 6 of the pump housing lie in planes which are inclined to each other and to the axis of the pump shaft. Accordingly, as the impeller rotates at low speeds, the blades 4 are compelled to flex axially. The point of minimum separation between the end walls 5 and 6 of the pump housing is designated by the numeral 22 and the point of maximum separation is designated by the numeral 23. As the impeller blades

2

rotate from point 22 to point 23 in a clockwise direction, the blades are continually expanding axially thereby increasing the volume of the space between adjacent blades and creating a suction at the inlet 20. As the impeller 5 rotates from point 23 to point 22, the blades are continually being compressed axially thereby reducing space between adjacent blades and forcing liquid out the outlet 21. It will be noted that on the pressure side of point 22 there is a pair of blades designated by the numerals 10 24 and 25 which at all times seal the pressure side of the impeller from the suction side and in a similar manner on the suction side of point 22 blades 25 and 26 seal the liquid pressure from the inlets 20. As the impeller rotates from the position illustrated in Fig. 3, the space 15 between the two blades 24 and 25 continues to decrease until the blade 25 reaches point 22 and any pressure built up between the blades is relieved by flexing of the blade 24. As the blade 25 passes point 22, the blade 26 starts to pass over the suction inlet 20 and the suction 20 created by the gradual increase of the space between the blades 25 and 26 draws liquid into the inlets 20. Because of the blades 24, 25 and 26, it is not possible at any time for liquid to flow from the pressure side of point 22 to the inlets 20.

The flexing of the impeller blades 4 is diagrammatically illustrated in the perspective view of Fig. 5. In this figure, unstressed positions of the blades is designated by the numeral 27 and the planes of the end walls 5 and 6 of the pump housing are designated by the numerals 30 28 and 29. Fig. 5 shows the position of the blades at slow speed rotation of the impeller. At higher speeds, the liquid pressure on the leading face of the blades causes them to bend rearward and separate from the sloped end walls. Therefore, the axial flexing of the 35 blades is no longer controlled by the sloped end walls during this phase of operation and the pump functions as a centrifugal rather than as a positive displacement pump under the conditions illustrated in Fig. 5.

Because there are two separate pumping cavities, one 40 above and one below the disc 3, it is possible to use the pump for pumping liquids from two separate sources. When the disc is symmetrically located with blades of equal projection on opposite sides, the pumping cavities will have equal capacity. By having the blades 4a on 45 one side of the disc 3 of greater axial projection than blades 4b on the other side of the disc as shown in Fig. 6, the pumping cavities will have unequal capacity. Inequality of pumping capacity may also be obtained by having one of the end walls of the pump housing at a 50 different inclination than the other.

By having the blades on opposite sides of the center disc 3, axial bending forces on the blades are balanced against each other. Radial bearing loads are eliminated because the blades are concentric with the pump shaft. 55 Many of the stresses present in pumps with radially deflecting blades are accordingly eliminated. The design permits very uniform stressing of the impeller blades which means that without exceeding the operating stress, the amount of flexing of the blades can be increased with 60 the resultant increase in pump capacity which is directly proportional to the amount of flexing of the blades. The blade configuration shown at 30 in Fig. 7 is preferable because the section 31 subject to the greatest bending moment has the greatest cross section.

It is not necessary that the disc 3 be circular so as to 65 divide the pump housing into two separate pumping cavities. The disc can be cut away between adjacent blades, for example, by notches extending inward from the periphery of the disc so there will be only a single pumping cavity between adjacent blades. With the disc 70 cut away, the same kind of pumping action will be obtained as the blades are axially flexed but, of course,

fluid can be pumped only from a single source because the disc will no longer block free fluid communication between its upper and lower sides. Since the disc acts as part of the structural support for the blades, it is advantageous to keep the part of the disc immediately adjacent the blades and hub as a structural part.

The embodiments of the invention in which an exclusive property or privilege is claimed are defined as follows:

1. A rotary pump having a housing with end walls having an axial separation which varies angularly about the axis of the pump from a maximum to a minimum and back to a maximum, a rotary impeller having a hub at the center, a tubular sleeve of flexible material united to the impeller concentric with and projecting axially from the hub, a plurality of angularly spaced flexible blades carried by the hub and bridging the space between the end walls and being deflected axially to change the volume between adjacent blades as the impeller is rotated, said blades having notches radially outside and adjacent said sleeve, said housing having a tubular projection radially outside and telescoped over and making sealing engagement with said sleeve and complementary to and received in said notches, and an inlet on the side of the housing in which the volume between adjacent blades is increasing and an outlet on the side of the housing in which the volume between adjacent blades is decreasing as the impeller is rotated.

2. A rotary pump having a housing with end walls having an axial separation which varies angularly about the axis of the pump from a maximum to a minimum and back to a maximum, and a rotary impeller having a hub at the center carrying two sets of angularly spaced flexible blades extending between the hub and the periphery of the impeller and with each set of blades projecting axially into engagement with a different end wall, each blade having an axially extending notch at its inner end, said housing having axially inward extending tubular projections complementary to said notches and extending from opposite ends of the housing into said notches, said impeller having tubular sleeves radially inside said tubular projections and projecting axially outward from the impeller and having outer ends telescoped in sealing engagement into said tubular projections of the housing, and said blades bridging the space between the end walls and being deflected axially to change the volume between adjacent blades as the impeller is rotated, and an inlet on the side of the housing in which the volume between adjacent blades is increasing and an outlet on the side of the housing in which the volume between adjacent blades is decreasing as the impeller is rotated.

3. A rotary pump having a housing with end walls with an axial separation a minimum at one point around the circumference of the housing, a rotary impeller having a hub at the center between the end walls and carrying two

sets of angularly spaced flexible blades, each set respectively projecting axially into engagement with a different end wall, said blades bridging the space between the end walls and being deflected axially to change the volume between adjacent blades as the impeller is rotated, said blades having at their inner ends notches extending axially inward from the end walls of the housing, said housing having axially inward extending tubular projections complementary to the notches and extending from opposite ends of the housing into said notches, said impeller having tubular sleeves radially inside said tubular projections and projecting axially outward from the impeller and having outer ends telescoped in sealing engagement into said tubular projections of the housing, and an inlet communicating with the housing on the side of said point in which the volume between adjacent blades is increasing as the impeller is rotated past said point and an outlet communicating with the housing on the side of said point in which the volume between adjacent blades is decreasing as the impeller is rotated past said point.

4. A rotary pump having a housing, a rotary impeller having a plurality of angularly spaced flexible blades with a sliding fit in the housing, said housing having a region of minimum axial length whereby the blades are deflected axially to change the volume between adjacent blades as the impeller is rotated past said region, said impeller having at its center flexible sleeves with free ends projecting axially in opposite directions, said housing having tubular projections radially outside and telescoped over said sleeves and making sealing engagement therewith, said blades having notches radially outside said sleeves and complementary to and receiving said tubular projections, and an inlet communicating with the space between the blades on the side of said region in which the volume between adjacent blades is increasing as the impeller is rotated past said region and an outlet communicating with the space between the blades on the side of said region in which the volume between adjacent blades is decreasing as the impeller is rotated past said region.
